TOOTHED SPATULA FOR DECORATING CAKES

Robert G. Andersen, Chicago, Ill.

Application November 1, 1954, Serial No. 32,898

Term of patent 7 years

(Cl. D44—1)

Fig. 1 is a top plan view of a toothed spatula for decorating cakes showing my new design;

Fig. 2 is a side elevational view taken from above Fig. 1;

Fig. 3 is a side elevational view taken from below Fig. 1;

Fig. 4 is an end elevational view taken from the right of Fig. 1; and

Fig. 5 is an end elevational view taken from the left of Fig. 1.

I claim:

The ornamental design for a toothed spatula for decorating cakes, as shown.
